PATENTED MAY 14, 1833.

7576X

J. DINSMORE.
FIRE ALARM.

James Dinson or, County of Penobscot, State of Maine

Petitions Pending.

The Schedule, referred to in these Letters, Patents, and working model of the same, containing a description in the words of the said James Dinson, himself of his improvement in the apparatus called the "Fire Alarm".

To all to whom these presents shall come.

Be it known, that J. James Dinson of Milltown in the County of Penobscot & State of Maine, have invented a new and useful Machine & Apparatus, for the purpose of a "Fire Alarm"; to act on the principle of self movement as a sentinel to give notice at the first attack of fire in season to prevent conflagration by that devouring element, and that the following is a full and exact description of the construction and operation of the said machine as invented by me.

The alarm to be given by a Machine, like the striking part of a common clock, detaching from it all the machinery except what is necessary for the hammer to strike the bell only, have the bell three times as large (or sufficient for the purpose) this part of the machine I don't claim as my invention, only what I attach to it & the purpose for which it is applied. Suffice to this part a latch, which is the only thing that prevents the alarm from operating, this latch is lifted by a separate Machine attached to the former consisting of a wheel with a small weight sufficient to keep the pinion straight, and allow it to stretch & shrink according to its length & state of the atmosphere and also to lift the latch when the fire line burns off by which it is held & let it run. - The fire line is made to run from store, I fasten at one end, & if it immediately above the funnel where the fire would most likely first come in contact with wood. - If present fire, from fire place, pass the line round in the corner, place pulleys, to let the line under easy, and in

X-7576

All other places where fire would most likely first attack the wood past the fire line, make it fast to the small weight wheel on the opposite side, so that when the line burns off, in any place the small weight will, after revolving upon the line attached to the latter, lift back sufficient to allow the fire line to burn & shrink will lift the catch when the alarm will commence to continue, until the striking weight reaches the floor.

This machine may be placed in the sleeping or watch room, and the fire line extended any distance to a store, factory, or other building and give the alarm in time to prevent damage by fire. —
